PIVOTED TOOL FOR BENDING THE EDGE
OF A PANEL ABOUT A SUPPORTING
FLANGE

Leon E. Willett, Detroit, Mich., assignor to Chamberlin Company of America, Detroit, Mich., a corporation of Michigan

Application June 9, 1945, Serial No. 598,510

2 Claims. (Cl. 153—16)

1

This invention relates to forming tools or implements, and more particularly to a special implement utilized for bending or forming the edge portions of a metal sheet or panel around the edge of a wall, flange or other support with which the sheet or panel is to be assembled.

One object of the invention is to provide a simple and highly effective tool for the purpose, capable of convenient operation by an operator working at an assembly bench or table, and adapted to produce a relatively permanent assembly of the parts worked upon in a manner to hold the sheet or panel flat and taut in its final position.

Still another object is to provide an implement of this kind capable of being moved along the work while lying on the bench, and arranged when operated to firmly hold the work and tool in proper relative positions, insuring uniform product.

Further objects of the invention in part are obvious and in part will appear more in detail hereinafter.

In the drawings,

Fig. 1 is a perspective view illustrating one suitable embodiment of the invention, part of a clamping frame being omitted; and

Figs. 2, 3 and 4 are similar sectional elevations, all on the line 2—2, Fig. 1, showing the tool applied to the work and illustrating various positions of the parts during operation.

While the implement is adapted for use in attaching any sheet to a supporting wall, flange or the like, it is intended more particularly for use during the manufacture and assembly of a certain type of protective screen such as shown, described and claimed, for example, in my application for Protective screen, filed May 4, 1945, Serial No. 591,983, to which reference may be had, if desirable or necessary. The screen of said application includes stationary and movable sheet metal frame members hinged together, the stationary member supporting a wire mesh screen panel. The drawings here show only the movable frame member, marked generally 10, made of fairly heavy sheet metal bent to the cross section shown and including a flat base or face portion 11, an outer cross flange or wall 12, an inner inclined wall 13 and a return supporting flange 14. The sheet or panel to be secured to the flange 14 is indicated at 15. It consists of wire screen made of any suitable strong material, such as steel wire of high tensile strength. Stainless steel may be employed but is not essential. The screen is intended to be so strong as to effectively resist attempts to cut or break it. Consequently, to bend an edge portion of this wire panel 15 around the flange 14 to form the return flange 16

is beyond the strength of the fingers and almost impossible with any ordinary tools, especially since the flange 16 is bent underneath supporting flange 14 and into a recess or cavity 17 where manipulation is difficult. The present implement solves all of the difficulties heretofore encountered in assembling these screen parts.

The implement comprises a suitable frame, marked generally 18, including L-shaped side members 19 connected at one end, as by welding, to a cross bar 20, of angle form, having a bottom flange 20a which serves as a presser to hold the work down, and at their other ends by a second angle member 21 which serves as a pressure abutment and tool locator by its engagement, when the tool is in working position, as shown in Fig. 2, with the inner surfaces of the frame base 11 and cross wall 12. In the side members 19 is mounted a cross shaft 22 supporting the side arms 23 of a yoke provided at one end with a handle 24 and connected at their opposite ends by a forming or bending member 25. This is elongated laterally, say four to six inches in length, and of uniform cross section from end to end. It has a foot portion 26 and a recess or channel 27 having a curved concave surface 28, as shown.

In use of the implement, the movable member of a rectangular screen frame of the form shown in said copending application is laid upon a work bench, table or other support, indicated conventionally at 30, with the cavity in the frame opening upwardly and with its cross wall 12 parallel to and near the edge of the table, as shown in Fig. 2. A plain rectangular wire cloth panel, 35 cut to proper size but with its edges unbent is then laid in place upon the frame member, the edges of such panel extending beyond the edges of the return flange 14, as shown. The tool or implement described is then laid in place, with its yoke and handle members extending upwardly and backwardly as shown. In this position the angle 21 of the frame rests in the angle between the base 11 and cross wall 12, while the cross shaft 22 lies just above the edge of the return flange 14. The toe of the foot 26 is above and near the outer edge of the wire cloth panel. Pressure is applied to the tool to hold it down and the operating handle is moved toward the operator, first to the position shown in Fig. 3 and finally down to horizontal position as shown in Fig. 4. During this movement the toe engages the free flange of the wire panel and bends it around the return flange 14 of the frame member. In the final position of the parts the concave surface of the channel 27 closely hugs the return of the wire screen and tightly pinches it, establishing a permanent set and securing the edge of the wire panel to the supporting flange 14.

The effect, of course, extends only along that portion of the wire screen engaged by the forming tool, say a matter of four to six inches of its length, neighboring portions of the wire panel bending downwardly only partially. The tool is then moved along the work to a new position and the next adjacent zone of the panel is secured in place by a similar operation, and so on repeatedly entirely around the frame.

Usually the wire panel is secured to the frame member first along one edge and then along its opposite parallel edge, after which the two remaining edges are secured in order in like manner.

If the wire of the panel is not too strong and heavy the downward pressure of the operator upon the operating handle may be sufficient to hold the tool down to the work, but, as a general rule, I prefer to provide the tool with any suitable hold-down means. In the arrangement shown I secure to each side of the frame, as by welding, a plate member 31 extending forwardly beyond the edge of the table and provided with a depending portion 32. These two depending parts may be attached in any suitable manner to a device by means of which the operator may apply downward tension with his foot, such as a foot treadle mounted upon a part of the table or even upon the floor. In the drawings, for simplicity of illustration, I show the two members 32 provided with extensions 33 connected by depending link 34 to the treadle 35 on which the operator can place his foot for exerting holding pressure.

Of course a tool of this kind must be designed and proportioned for use according to the shape, size and proportions of the particular screen frame with which it is designed to be used. That is particularly true with respect to the position and relative relation of the pressure abutment angle member 21 and the cross shaft 22. But, if desired, where screen frames of different width are to be worked upon, the side members 19 may be provided with several holes 36, in any pair of which the shaft may be mounted, as will be readily understood.

The implement described is of simple form but is highly efficient in operation. Since the wire screen is heavy and strong it lies flat in its unbent condition and the act of bending its edges around the holding flanges 14 applies tension to the wire cloth, and the permanent assembly maintains that tension.

Cross bar 20 operates as a clamp or anchor to confine and hold down the wire screen panel during the bending operation, while the angle member 21 not only serves as a guide to correctly locate the apparatus with reference to the work, but also as a pressure abutment or fulcrum to hold the tool frame stationary and transmit pressure to the base and cross flange of the frame member being operated upon. The forming member is elongated to extend along a reasonable length of the work and turns about an axis close to but within and above the edge of the flange around which the panel edge is being bent, and also is recessed to produce and conform to the semicylindrical form taken by the panel at the bend therein. Thus it closely hugs the work and in its final position produces the necessary squeeze to tightly pinch the parts together.

Other advantages of the invention will be apparent to those skilled in the art.

What I claim is:

1. Apparatus for assembling a bendable panel

with an elongated frame member of hollow chambered form provided with a base which along one edge supports a flange lying in a plane parallel with the base but spaced therefrom to provide an open cavity, and which along its opposite edge supports a wall lying opposite the open cavity, comprising a support, a presser member mounted thereon and adapted to engage the upper surface of a panel lying upon said flange, an abutment member depending from said support and adapted to extend downwardly into the chamber of the frame and engage its base and wall, and a forming lever pivoted in the support on an axis parallel to and above the lower surface of the presser member and between said presser and abutment members and provided with a rigid elongated bending foot having a toe portion adapted upon swinging movement of the forming lever foot downwardly between the presser and abutment members to thereby engage an edge portion of the panel and bend the same around the edge of the frame flange and through said opening into said cavity to a position in which it is in close contact with the lower surface of said flange and is concealed from view.

2. Apparatus for assembling a bendable panel with an elongated frame member of hollow chambered form provided with a base which along one edge supports a flange lying in a plane parallel with the base but spaced therefrom to provide an open cavity, and which along its opposite edge supports a wall lying opposite the open cavity, comprising a support, a presser member mounted thereon and adapted to engage the upper surface of a panel lying upon said flange, an abutment member depending from said support and adapted to extend downwardly into the chamber of the frame and engage its base and wall, and a forming lever pivoted in the support on an axis parallel to and above the lower surface of the presser member and between said presser and abutment members and provided with a rigid elongated bending foot having a toe portion laterally offset from and extending endwise beyond the lever pivot, said lever also having an open ended channel lying between its pivotal axis and said foot, said toe portion being adapted upon swinging movement of the forming lever foot downwardly between the presser and abutment members to thereby engage an edge portion of the panel and bend the same around the edge of the frame flange and through said opening into said cavity to a position in which it is in close contact with the lower surface of said flange and is concealed from view and the bend in said panel lies within the lever channel and is applied to the flange by lever pressure based by said abutment member upon the frame wall.
